UNITED STATES PATENT OFFICE

118,431

DESIGN FOR A TEXTILE FABRIC

Benjamin M. Kaufman, New York, N. Y.

Application October 11, 1939, Serial No. 87,618

Term of patent 3½ years

To all whom it may concern:

Be it known that I, Benjamin M. Kaufman, a citizen of the United States of America, residing in New York city, in the Borough of Manhattan, county and State of New York, have invented a new, original, and ornamental Design for a Textile Fabric, of which the following is a specification, reference being had to the accompanying drawing, forming part thereof, wherein the figure is a plan view of a piece of textile fabric showing my new design.

The characteristic feature of my design resides in the alternating rows of black and white yarns in chevron-like form, the alternate rows becoming thicker as they approach the points of chevrons, forming in addition to the chevron-like appearance, alternating stripes predominantly white and predominantly black.

I claim:

The ornamental design for a textile fabric, substantially as shown and described.

BENJAMIN M. KAUFMAN.
